PAPER BAG.

No. 904,167.

Specification of Letters Patent.

Patented Nov. 17, 1908.

Application filed February 14, 1906. Serial No. 800,992.

To all whom it may concern:

Be it known that I, HOWARD G. WIDMER, a citizen of the United States, and a resident of the borough of Brooklyn, in the county 5 of Kings and State of New York, have invented certain new and useful Improvements in Paper Bags, of which the following is a specification.

This invention relates to improvements in 10 paper bags.

The invention, broadly speaking, seeks, by efficient and inexpensive means, to facilitate the opening out of a bag from its flat or collapsed state and without necessitating the 15 insertion of the hand into the bag.

The invention also seeks to accomplish the result stated with reference to paper bags of the simpler construction, and also by means which may be of a character capable 20 of being formed on or applied to the paper with convenience and at small cost.

Heretofore the paper bags, in most general use, are of the plain tucked variety, consisting of a tube having infolded side tucks 25 and a bottom formed by turning over one end and pasting it down to one of the sides of the bag. This turned over portion forms a folded bottom closure which extends transversely and substantially straight across the 30 entire width of the bag. Of course, the corners of this fold might be clipped off to facilitate pasting and still the closure would have a portion which extended the entire width of the bag. These plain tucked bags 35 are sold, of course, in a flat or collapsed state. These bags are inexpensive, and are sold in large quantities for this reason. They have, however, certain serious defects. They cannot be properly opened out by an 40 in-rush of air, nor by the first entrance of the filling material. They therefore require to be opened out by inserting the hand and pressing out the tucks at the bottom. This, of course, requires time and considerable 45 care to avoid the formation of hap-hazard folds at the bottom corners, which is very objectionable. Furthermore, these bags, when opened out or filled, do not have flat bottoms, the bottoms being more or less 50 rounded. This is another defect. The desirability of overcoming these defects in a bag has been long recognized, and accordingly, bags of various constructions have 55 been proposed with this object in view. These proposed bags, however, could only

be made at a very considerable increase in the cost of manufacture, and are objectionable for this reason. Again, in the case of at least one variety of these proposed bags, the bag does not have a flat bottom and does 60 not open out with the requisite promptness and reliability.

In accordance with the present invention a bag is provided in which the defects and objections stated are entirely overcome. The 65 bags to which this invention applies are of this plain tucked variety in which the unaltered tube or collapsed bag blank has its bottom margin folded over bodily upon itself and secured to a side face of the bag, usually 70 by paste, and the tube is formed of one piece of material, the folded margin or bottom closure therefor extending across the entire width of the bag. In this specification, the expression "having infolded side tucks and 75 a folded bottom closure extending substantially straight across the entire width of the bag," defines the above described plain tucked bag to which this invention applies and the expression is intended to distinguish 80 over the bag known to the trade as the "automatic bag" on which diamond folds are made in the bags and a ready made flat bottom is formed and laid over on one side face of the bag, the bottom closure in this auto- 85 matic bag being formed by a flap in the middle of this folded over, ready made bottom and not extending across the entire width of the bag. Said expression likewise distinguishes over the bag in which the plies of the 90 tucks are infolded near the bottom of the blank and then the bottom margin folded over upon a side face of the bag to form a closure and lock the infolded plies in place. In this type of bag, also the bottom closure 95 does not extend across the entire width of the bag. In fact, the expression used is intended exclusively to define the cheap, plain 100 type of bag described.

With this invention expensive folding of 100 tuck plies and bag sides is not resorted to but simple means, which may be applied to a collapsed bag with convenience and despatch, is employed to aid the flexure of the bag material along the localities where flexure is required in opening out the bag, and in opening it out so as to form a flat bottom. And these means for aiding flexure may be and preferably are of such a character as to be negligible as regards increas- 110

ing the cost as compared with those proposed heretofore for the same general purposes.

In the type of bag referred to above as the plain tucked bag, the depth of the tucks determines points on the side edges of the bag, and these points, in turn, naturally determine the approximate corners of the bag bottom when the bag is opened out. It is through these points that the sides of the bag 10 and the tucks tend to flex when the bag is opened out by inserting the hand and by simultaneously pushing up the bottom and smoothing the sides and the tucks. These points, therefore, determine the natural lines of flexure.

In carrying out the invention a corrugation is specially formed in the collapsed bag through all its thicknesses and along its lines of flexure. Thus, each thickness will have 20 its own corrugation consisting of two contiguous creases or an alternate ridge and depression, the ridge of one face of a thickness constituting a depression on the opposite face of such thickness. It will, therefore, 25 be seen that each thickness will have at least one crease whose concavity will face in the proper direction and each crease will, in consequence, aid such thickness to flex in the proper direction notwithstanding the fact 30 that various thicknesses must flex in opposite directions in opening out the bag. Therefore in the preferred form of the invention all the natural lines of flexure are provided 35 with means for aiding flexure. It is to be understood, however, that various methods of manufacture may render other disposition of the means for aiding flexure more desirable.

The preferred form of the invention is 40 illustrated in the drawings forming part of this specification, in which like reference numerals designate corresponding parts or localities and in which:

Figure 1 illustrates a collapsed bag in side 45 elevation with portions of one side and of the tucks broken away. Fig. 2 is a similar view showing the opposite side from that shown in Fig. 1 and with the top portion of the bag removed. Fig. 3 is an enlarged sectional 50 elevation on the line 3-3 of Fig. 1. Fig. 4 is a sectional elevation of the bag opened out until its bottom is approximately flat, and provided with corrugations. Fig. 5 is a side elevation of a collapsed bag with portions 55 removed to show the creases on the tucks and Fig. 6 is a perspective view of a bag partially opened so that the creases along the lines of flexure of the tucks are visible.

Referring now more particularly to the 60 drawings: Fig. 6 illustrates a bag which has been partially collapsed after having been opened out and naturally creased until there are definitely defined creases along the lines 65 where the sides of the bag and the bottom intersect, that is, along the lines of flexure 1 and

2 of the sides 3 and 4 respectively. In addition to these creases along the lines of flexure 1 and 2 there are two transverse creases 5 and 6 across the tucks which would lie directly beneath the lines 1 and 2 if the bag 70 were again fully collapsed. There are also two oblique or diagonal creases 7 and 8 extending across the tucks, from the intersection of lines 5 and 6 with the side edges 9 and 10 respectively, until they intersect the edge 75 11 at the bottom of the collapsed bag. For the bag to open out until its bottom is flat it is necessary that something form this bottom. In fact, the bottom is formed by the portions 80 of the sides 3 and 4 below the lines 1 and 2, which are folded together when the bag is collapsed and which must each be of an extent equal to the width of a tuck fold or the depth of the tucks. Thus it is that the depth 85 of the tucks determines the lines 1 and 2 and consequently the points where they intersect the side edges 9, 10, 11 and 12, which subsequently are the corners of the bag bottom. It is obvious that these additional creases do not exist in and are not essential to the bag 90 when collapsed. However, the bag, when collapsed, possesses several creases which are essential and are made during the process of manufacture. Thus each infolded side tuck possesses three creases. Two of these are 95 where the tucks join the sides of the bag designated by the reference numerals 9 and 10, 11 and 12 and one where the tuck is folded on itself designated by 13 and 14. The sides 100 of the bag themselves also possess one crease along the bottom edge 11. To distinguish the lines of flexure 1, 2, on the sides 3 and 4; the lines of flexure 5, 6, 7, and 8 on the folds 105 15 and 16; and the similar lines of flexure 5, 6, 7 and 8 on the tuck folds 17 and 18, but not 110 shown in Fig. 6; from the lines of flexure essential in the collapsed bag, they are termed lines of flexure which the bag has when it is opened out until its bottom is approximately flat, in addition to the lines of flexure along 115 the folds or creases essential in the collapsed bag.

As the bag is opened out until its bottom is approximately flat the paper walls of the bag must bend in certain definite directions, 115 that is, they form creases which have their several concavities on a definite face or faces of the wall or walls. For instance, the concavities of the creases along lines of flexure 1 and 2 are on the inner face of the sides 3 and 4 respectively, and if the bag were collapsed 120 would come face to face. The concavities of the creases along the lines of flexure 5 and 6 are likewise on the inside faces of the tuck folds, 15 and 16 respectively, but as the tuck 125 is infolded when the bag is collapsed the convexities of these folds would come face to face instead of the concavities. The creases along the lines of flexure 7 and 8 have their 130 concavities on the outside faces of the tuck

5 folds 15 and 16 unlike those along the lines 5 and 6 and would have their concavities face to face when the bag is again collapsed.

In order that the bag may be opened out 5 with convenience and despatch it is proposed to form creases along the lines of flexure before the bag is ever opened out and in a manner so that they will exist as nearly as possible like the creases which would 10 necessarily be formed in the bag by opening it out and forming the bottom by hand. Owing to the varied positioning of these natural creases formed by opening out the bag, it is difficult to form artificially at one 15 operation, a single crease along each line of flexure so that each crease will have its concavity lying on the proper face of the bag wall. In order to overcome this objection the collapsed bag is passed through dies 20 which form a plurality of contiguous creases or, in the preferred form, a complete corrugation, comprising a ridge and a depression, approximately along the lines of flexure 1 and 2 of the sides, and obliquely 25 across the corners of the bag as shown at 19, 20 and 21, 22 along lines overlying the lines of flexure 7 and 8. This creasing or fluting involves the several thicknesses of the material of the collapsed bag and of the infolded 30 tucks and as a result, produces at least one crease approximately along each line of flexure which has its concavity lying on the proper face of the bag wall at that locality. The bag, when forced through the air until 35 the sudden inrush of air forces out the tucks, then readily selects the proper crease on which to flex and opens out automatically, without additional aid, until its bottom is approximately flat and the tucks have been 40 transformed into approximately flat walls. This automatic selection of the proper crease is best illustrated in Fig. 4, while Figs. 3 and 5 illustrate how the creases or convolutions involve the entire thicknesses of the 45 collapsed bag.

It is to be understood that the expression "along a line of flexure" does not mean that the plurality of contiguous creases or corrugations must continue throughout the entire 50 extent of the line of flexure. In some cases

they may be intermittent if desired. Furthermore any material suitable may be employed instead of paper, although paper is preferred.

While the preferred form and adaptation 55 of this invention has been described and illustrated, various combinations and modifications of details are considered to be within the scope of this invention as particularly set forth in the following claims:—

1. In paper bags, a bag comprising a tube formed of one piece of material and having infolded side tucks and a folded bottom closure extending substantially straight across the entire width of the bag; said bag being provided, along one or more lines of flexure, 60 with a corrugation which is especially formed through all the thicknesses of the collapsed bag.

2. In paper bags, a bag comprising a tube 70 formed of one piece of material and having infolded side tucks and a folded bottom closure extending substantially straight across the entire width of the bag; said bag being provided with a corrugation specially 75 formed approximately at angles of 45° to the side edges of the bag across the bottom corners of the bag and extending through all the thicknesses of the collapsed bag.

3. In paper bags, a bag comprising a tube 80 formed of one piece of material and having infolded side tucks and a folded bottom closure extending substantially straight across the entire width of the bag; said bag being provided with a corrugation specially 85 formed approximately at angles of 45° to the side edges of the bag across the bottom corners of the bag and with a corrugation formed straight across the collapsed bag 90 parallel to the bottom closure, both of said corrugations extending through all the thicknesses of the collapsed bag.

In testimony whereof, I have signed my name to this specification, in the presence of two subscribing witnesses.

DISCLAIMER.

904,167.—Howard G. Widmer, Brooklyn, N. Y. PAPER BAG. Patent dated November 17, 1908. Disclaimer filed January 21, 1910, by the assignee, *Continental Paper Bag Company*.

Enters this disclaimer of claim 1 and also of claim 2 of said Letters Patent, which claims are in the following words, to wit:

"1. In paper bags, a bag comprising a tube formed of one piece of material and having infolded side tucks and a folded bottom closure extending substantially straight across the entire width of the bag; said bag being provided, along one or more lines of flexure, with a corrugation which is especially formed through all the thicknesses of the collapsed bag.

"2. In paper bags, a bag comprising a tube formed of one piece of material and having infolded side tucks and a folded bottom closure extending substantially straight across the entire width of the bag; said bag being provided with a corrugation specially formed approximately at angles of 45° to the side edges of the bag across the bottom corners of the bag and extending through all the thicknesses of the collapsed bag."—[Official Gazette, February 1, 1910.]

5 folds 15 and 16 unlike those along the lines 5 and 6 and would have their concavities face to face when the bag is again collapsed.

In order that the bag may be opened out 5 with convenience and despatch it is proposed to form creases along the lines of flexure before the bag is ever opened out and in a manner so that they will exist as nearly as possible like the creases which would 10 necessarily be formed in the bag by opening it out and forming the bottom by hand. Owing to the varied positioning of these natural creases formed by opening out the bag, it is difficult to form artificially at one 15 operation, a single crease along each line of flexure so that each crease will have its concavity lying on the proper face of the bag wall. In order to overcome this objection the collapsed bag is passed through dies 20 which form a plurality of contiguous creases or, in the preferred form, a complete corrugation, comprising a ridge and a depression, approximately along the lines of flexure 1 and 2 of the sides, and obliquely 25 across the corners of the bag as shown at 19, 20 and 21, 22 along lines overlying the lines of flexure 7 and 8. This creasing or fluting involves the several thicknesses of the material of the collapsed bag and of the infolded 30 tucks and as a result, produces at least one crease approximately along each line of flexure which has its concavity lying on the proper face of the bag wall at that locality. The bag, when forced through the air until 35 the sudden inrush of air forces out the tucks, then readily selects the proper crease on which to flex and opens out automatically, without additional aid, until its bottom is approximately flat and the tucks have been 40 transformed into approximately flat walls. This automatic selection of the proper crease is best illustrated in Fig. 4, while Figs. 3 and 5 illustrate how the creases or convolutions involve the entire thicknesses of the 45 collapsed bag.

It is to be understood that the expression "along a line of flexure" does not mean that the plurality of contiguous creases or corrugations must continue throughout the entire 50 extent of the line of flexure. In some cases

they may be intermittent if desired. Furthermore any material suitable may be employed instead of paper, although paper is preferred.

While the preferred form and adaptation 55 of this invention has been described and illustrated, various combinations and modifications of details are considered to be within the scope of this invention as particularly set forth in the following claims:—
